UNITED STATES PATENT OFFICE.

JOHN THOMAS WAY, OF WELBECK STREET, MIDDLESEX COUNTY,
GREAT BRITAIN.

IMPROVEMENT IN ELECTRIC LIGHTS.

Specification forming part of Letters Patent No. 33,458, dated October 8, 1861.

To all whom it may concern:

Be it known that I, JOHN THOMAS WAY, of Welbeck Street, in the county of Middlesex, in the Kingdom of Great Britain and Ireland, have invented a new and useful Improvement in Obtaining Light by Electricity; and I do hereby declare that the following is a full, clear, and exact description of the same, reference being had to the accompanying drawings, making part of this specification.

The great obstacle to the successful application of electricity to the purpose of illumination has been the difficulty experienced in the adjustment and regulation of the position of the points of the electrodes of carbon which have been generally used.

This invention consists principally in the substitution for fixed electrodes of carbon or other material of two flowing electrodes, such as two streams of mercury, one connected with each pole of the battery and issuing in two jets, such streams meeting each other at a point where the separation of the particles of either or both streams commences, as will be herein-after fully described. Instead, however, of a single stream of mercury or other material, either or each of such flowing electrodes may be composed of two or more of such streams.

In the accompanying drawings, Figure 1 represents an elevation, partly in section, of an electric lamp illustrating my invention. Figs. 2 and 3 are vertical sections of modifications of the construction and arrangement of the jets.

Similar letters of reference indicate corresponding parts in the several figures.

A A' (Fig. 1) are two cisterns, of iron, glass, slate, or other suitable material, from which mercury is conveyed by pipes a b and a' b', fitted with stop-cocks g g' to jets c c', made of infusible clay or other substance capable of bearing great heat and having orifices as small as they can be conveniently made, from which the mercury will issue in constant streams, which constitute the flowing electrodes. The two cisterns A A' are to be isolated from each other and arranged at any height above the jets—say, from six to thirty inches or more, according to the pressure desired to be obtained—and to enable the pressure to be regulated they are made adjustable upon their support B, and the pipes a a' are made of india-rubber or other flexible material. The pressure of the streams may be ob-

tained by mechanical means instead of by the column of mercury. To prevent the escape of mercurial vapor the jets are surrounded by and inclosed within an air-tight glass bell-shade, C, supported on an iron plate, D, through which the pipes b b', for supplying the jets, pass. These pipes are made adjustable in such manner as to enable the two streams of mercury to be thrown upon each other at any desired angle or in any desired direction. Various modes of adjustment may be adopted, the insulating of the electrodes from each other always being kept in view. In Fig. 1 the adjustment is provided for by fitting the pipes b b' to the plate D with ball-and-socket joints, the sockets i i' being formed in or upon the plate D, and the balls d d' upon iron sleeves through which the pipes b b' pass, the said pipes being made of clay, and each in the same piece with its respective jet.

In Fig. 2 the pipes b b' are fitted to slide and turn in sockets e e', provided for them in the plate D. The pipe b is represented as being fitted to a socket suitably inclined toward the socket of b', but b' is represented as fitted to an upright socket, but having its upper part or its jet bent at a suitable angle toward the other pipe and jet. Both pipes may be like b or both like b', as under either arrangement they can be adjusted so that the streams issuing from their jets can be made to meet in the desired point. The pipes b b' in this figure also are supposed to be made of clay. In both of the two modes of adjustment shown in Figs. 1 and 2 adjusting-screws may be used to obtain a more delicate adjustment of the pipes b b' and jets than can be got by hand, and set-screws used to secure the pipes when properly adjusted.

Fig. 3 shows the two jets constructed in one piece of clay, I. In this construction they cannot be adjustable, but are made at such an angle to each other as shall have been ascertained to be most desirable, and whatever adjustment of the streams is necessary can be obtained by elevating or lowering one or both of the mercury-cisterns. The piece of clay I is fitted and cemented air-tight and mercury-tight into an opening provided for it in the plate D. The jets are molded in the piece of clay I, by means of cores made of a single piece of thread bent and held at a proper angle.

This thread is left in the clay to be destroyed in burning the clay.

From the plate D a pipe, H, descends to a receiver, J, below to convey thereto the mercury which falls from the jets on the plate D. In Fig. 1 this pipe and receiver are shown as constituting a stand for the plate D, but in Figs. 2 and 3 a separate stand, K, is represented.

An upright glass cylinder, closed air-tight at its top and bottom by iron-plates, may be substituted for the bell-shade C and plate D, and in that case, if one of the jets be made to enter the said cylinder through the bottom plate, and another through the top plate, no insulation from the said plates is necessary, as the glass cylinder serves to insulate the electrodes from each other. The glass cylinder or bell-shade should be as infusible as possible and well annealed. Its distance from the point of light is a matter of some importance, that it may be heated to such a degree as to prevent the mercury from adhering to it—that is to say, above the boiling point of mercury—but not to such a degree as to be in danger of being cracked or fused. It is desirable that this glass should be protected from rain when the apparatus is used in the open air, and an advantage is gained in shielding it in all cases from currents of cold air.

The connections of the two electrodes with the conducting-wires of the opposite poles of the battery or of a magneto-electric machine may be made at any point between the cisterns and the jets. The connections having been made, the apparatus is set in operation by opening the stop-cocks *g' g'*. In explanation of the operation I will state, as is well known, that when a current of electricity is made to pass through a conductor, such as a thin wire of metal, which is insufficient in conducting power to allow of the ready passage of the electricity, that heat is generated, and if the current be powerful the conductor becomes red or white hot. The small streams of mercury, issuing from the jets *c' c'* and meeting each other, have the character of a fine wire. Now, it will be found on examination that at a distance from the orifices of the jets depend-

ent upon the force with which the streams are made to issue and the size of the streams, the dark metallic appearance of the mercury changes to a silvery hue, owing to a partial separation of its particles from each other. At or about these points the greatest resistance to the passage of the electricity occurs, and it is at such point in each stream, or in one of them, at least, that the streams should meet each other, and at the point of meeting the light will be obtained.

The other materials, besides mercury, whose use I have contemplated for electrodes, are the filings of iron and other metal, powdered charcoal, and fusible metals, kept liquid by heat; but I consider mercury preferable to any of these substances.

In addition to what I have described, I propose to employ means of heating the mercury before conveying it to the jets. I also propose to make and break very rapidly the electric circuit, by which the elements of the battery are very much economized and the quality of the light is not sensibly altered. This may be effected by means of a revolving electro-magnet, which is kept in motion by the power of the battery employed to obtain the light. I also propose to employ springs or keys of suitable construction, to be worked by the finger or by other means, to break and make the electric current at suitable intervals for the purpose of instantaneously extinguishing and reproducing the light for giving signals or telegraphing by means of flashes of greater or less duration. And I further propose, by means of clock-work or other mechanical agency, to produce the repetition of the flashes at suitable and regular intervals, to adapt my invention for light-house purposes.

What I claim as my invention, and desire to secure by Letters Patent, is—

The employment in obtaining light by electricity, of two flowing electrodes, substantially as herein specified.

J. THOMAS WAY.
